DESIGN FOR A DRESS.

Application filed January 14, 1925. Serial No. 12,044. Term of patent 14 years.

To all whom it may concern:

Be it known that I, EDITH SIEGMUND, a citizen of the United States, residing at San Juan, Porto Rico, have invented a new, original, and ornamental Design for Dress, of which the following is a specification, reference being had to the accompanying drawing, forming part thereof, wherein the dress is distinguished by means of two spaced ornamental rectangular inserts A A, located on opposite sides of the front, an ornamental rectangular area B below each insert and formed by a plurality of spaced vertical lines of openwork, a centrally-disposed ornamental series C of vertical lines of openwork extending downwardly from the neck opening towards the inserts, and an ornamental series D of tucks located on each side of the neck opening.

I claim:

The ornamental design for a dress, substantially as shown and described.
